BEADING AND FLANGING MACHINE

Ed Laxo, Oakland, Calif., assignor to Continental Can Company, Inc., New York, N. Y.

Application April 20, 1951, Serial No. 222,034

4 Claims. (Cl. 153—2)

1

This invention relates to a machine for beading and/or flanging can bodies.

Can bodies are frequently beaded, that is they are formed with one or more peripheral grooves, to strengthen the metal. By this means it is possible to use a thinner gauge metal in forming can bodies.

A can beader should operate at high speed and should perform the beading operation uniformly and accurately. Also, it should operate so as not to damage or deform can bodies during the beading operation. It is also desirable to provide adjustment means to vary the spacing and number of beads and to adjust the machine for can bodies of different diameters and different heights.

Machines heretofore used for beading operations have been relatively complex in their design and operation. In beading a can body it is necessary to provide a male die or seaming tool and a female die or chuck. The male die bears against the outer surface of the can body and the female die bears against the inner surface of the can body. In prior can body beaders, the design and operation of these dies have been such that their movements are complex and their timing is difficult.

It is an object of the present invention to provide an improved machine which is capable of performing beading or flanging or other similar operations on can bodies or the like.

It is a further object of the invention to provide a machine of the character and for the purpose described which is capable of high speed, dependable and accurate operation.

It is a further object of the invention to provide means for adjusting a can body beader or flanger to vary the number and spacing of the beads and to adjust the machine for can bodies of different diameters and heights.

Yet another object of the invention is to provide a machine of the character and for the purpose described which is simple in design and includes fewer moving parts and fewer timing difficulties than machines previously designed.

Still another object of the invention is to provide a machine which is capable of performing both beading and flanging operations on can bodies.

These and other objects of the invention will be apparent from the ensuing description and the appended claims.

One form of the invention is illustrated by way of example in the accompanying drawings and is described in detail hereinafter.

2

In the drawings:

Figure 1 is a fragmentary view partly in longitudinal section and partly in elevation of the machine of the invention.

Figure 2 is a vertical section taken along the line II—II of Figure 1. Figure 2 also shows the feed screw.

Figure 3 is a fragmentary sectional view on a larger scale than that of Figure 1, showing the beading and flanging chucks and bars in detail.

Figure 4 is a section taken along the line IV—IV of Figure 5, and it shows the pivotal means for mounting the beading spindles.

Figure 5 is a view in elevation of a beading chuck and spindle as seen from the top of Figure 4.

Figure 6 is a fragmentary view, partly in section and partly in elevation, showing the adjustable mounting means for the beading spindles.

Figure 7 is a fragmentary view, partly in section and partly in elevation, showing the means for mounting the tie rods.

Referring now to the drawings and more particularly to Figures 1 and 2, the machine is generally designated as 10 and it includes a body feed assembly 11 for feeding can bodies 12 to the machine, and an exit chute 13 for removal of can bodies after completion of the beading and flanging operations. The feed assembly 11 includes a feed screw 14 which is journaled in bearings 15 and is driven by means including a shaft 16 in timed relation to operation of the machine as a whole. The feed assembly 11 also includes side rails or bars, two of which are shown at 17 and 18.

Referring more particularly to Figure 1, two of the several beading and flanging assemblies are there shown in section and are designated as 25. As will be apparent from Figure 2, there are six of the assemblies 25 disposed equi-angularly about a central drive shaft 26. Of course a greater or lesser number of assemblies may be employed. The drive shaft 26 is journaled in bearings, one of which is shown at 27 and which are fixed to the frame 28 of the machine. The shaft 26 is driven by suitable means including a gear 29.

Each of the assemblies 25 comprises identical left- and right-hand portions 25a and 25b respectively. The description, for the most part, will be with respect to the left-hand assembly 25a. A spider 30 is keyed at 31 to the shaft 26 and it will be seen that the spider can be adjusted lengthwise of the shaft for a purpose described hereinafter. When suitable adjustment has been

made, the spider is clamped in adjusted position by means of a screw 32. The spider 30 is formed with arms 33 which slidably support slide members 34, one of which is best shown in Figure 4. As there shown, the spider arms 33 are formed with L-shaped, machined portions 35 to slidably receive the slide member 34 and gib 36 are provided to retain the slide in place.

The slide member 34 includes a sleeve bearing 37 within which a spindle 38 is rotatable. Bushings 39 are provided in which the spindle 38 is freely rotatable. Suitable means may be provided for positively rotating the spindle 38, e. g. a sprocket 40 which is keyed at 41 to the spindle and a chain 42 extending about the perimeter of the machine and meshing with the sprockets. The chain 42 is suitably anchored at one point (not shown) to the frame of the machine so that rotation of the sprockets 40 about the axis of shaft 26 will cause rotation of the sprockets and hence of the spindles 38 about their axes. The sprocket 40 is keyed to the spindle for sliding movement along the length of the spindle, so that as the spindles are reciprocated in the manner and for the purpose described hereinafter, the sprockets 40 will nevertheless remain in the same position.

It will be apparent that, as the shaft 26 and with it the spider 30 rotate, each slide member 34 will also rotate and its spindle 38 will rotate about its own axis and about the axis of the drive shaft 26. A reciprocating motion is also imparted to each slide member 34, and with it to its spindle 38, by means of a cam 45 which abuts the outer end of the sleeve 30. A bushing 46 is provided so that the shaft 26 is freely rotatable within the cam 45. The cam 45 is formed with an annular groove 47, and it will be seen from an inspection of the left-hand cam 45 that the cam groove 47 has a high point at 47a corresponding to the advanced or innermost position of the spindle 38, and a low point at 47b corresponding to the retracted or outermost position of the spindle 38. A roller 48 rides in the cam groove 47 and is connected, as by means of a stub shaft 49 and a nut 50, to the slide 34.

Referring more particularly to Figure 3, it will be seen that, at its inner end, each spindle 38 is fixed to a chuck or female die 51. In can body beaders of prior design the dies corresponding to the dies 51 are called spindles, but for convenience of description and to distinguish them from the spindles 38, they will be referred to herein-after as "chucks."

The right-hand chuck 51 is formed in three parts, i. e., a cap or flanging portion 52 which is formed with an annular flanging shoulder 53, an intermediate portion 54 which is formed with annular beading grooves 55 and an end portion 56 which is also formed with one or more beading grooves 57. The several parts are clamped together and to the spindle 38 by means of a cap screw 58 which is countersunk in a recess 59. The left-hand chuck 51 is of generally similar construction but its end portion 56a is smaller and is not formed with a beading groove.

Each spider 30 also supports a pair of spaced guide plates 65 which are formed with holes 66 to receive, and permit passage of, the chucks 51, and it also supports a pair of spaced turret plates 67 which are formed with pockets 68. The pockets 68 are best shown in Figure 2 and, as there shown, rollers 69 are rotatably mounted at the outer edges of each pocket 68. As shown in

both Figures 1 and 2, cap screws 70 serve to bolt the turret plates 67 to the spider 30.

The chucks or female dies 51 are intended to cooperate with a male die or beading assembly 75 which is best shown in Figure 3. Referring thereto, left- and right-hand support rings 76a and 76b are provided on opposite sides of the beading and flanging station. As shown in Figures 2 and 7, tie bars or rods 77 are provided at spaced intervals about the support rings 76a and 76b and are clamped thereto as by means of split collars 78 and cap screws 79. As shown in Figure 7, the tie rods 77 are clamped to the frame of the machine by means of screws 80.

A suitable number of cross bars 81 are provided as shown in Figure 2. As shown in Figure 3, each cross bar 81 extends between and is adjustably mounted on the support rings 76a and 76b by means of screw assemblies 82. Each of the screw assemblies 82 comprises a tubular screw 83 which is formed with an axial passage 84 through which a screw 85 extends. The inner end of the screw 85 is threaded at 86 into one end of the cross bar 81. The outer or tubular screw 83 extends through a passage 87 formed in the lip 88 of the support ring 76a or 76b and, as will be seen, the passage 87 is of sufficiently large diameter to allow a certain amount of play of the screw 83. At its inner end the screw 83 is threaded to a square nut 84a which is located so closely to the support ring that it cannot turn and will not, therefore, loosen during operation of the machine. A lock nut 89 is also provided.

It will be apparent that cross bars 81 can be adjusted with great precision. Thus, they can be moved inwardly or outwardly and they can be warped, by manipulation of the screw assemblies 82. Thus, if it is desired to move inwardly the right-hand end of the cross bar 81 shown in Figure 3, it is merely necessary to screw the right-hand screw 83 inwardly. If it is desired to move the right-hand end of the cross bar 81 outwardly, it is merely necessary to screw the right-hand screw 83 outwardly, then tighten the lock nut 89. The relatively large diameter of the holes 87 allows some play to the screws 83, hence permits warping the cross bars 81.

The cross bar 81 is formed with grooves 95 to receive beading bars 96 and flanging bars 97. The bars 96 and 97 are arcuate bars which lie on an arc extending from a receiving station A to a delivery station B (see Figure 2). They are fixed to the cross bars 81 by means of cap screws 98. Each of the beading bars 96 is formed with a beading rib 99 and each of the flanging bars 97 is formed with a beveled flanging shoulder 100. The ribs 99 are of a rounded shape calculated to form annular grooves or beads 101 in a can body, in cooperation with the beading grooves 55 of the chucks 51, and the beveled shoulders 100 are of a convex shape calculated to form flanges 102 in cooperation with the shoulders 53 of the chucks 51.

It will be apparent from an inspection of Figures 1 and 3 that, as the drive shaft 26 rotates the spindles 38 and the chucks 51 will also rotate about the axis of the drive shaft 26 and each of the spindles and chucks will also rotate about their own axis. It will also be apparent that the cams 45 will cause each pair of spindles 38 and chucks 51 to reciprocate between an outermost or retracted position as shown at the lower edge of Figure 1 and an innermost or advanced position as shown at the upper edge of Figure 1 and in Figure 3. This latter operation is timed so

that, as each can body is delivered at the delivery station A by the feed screw 14 and is seated in a pocket 68 of the turret plates 67, the spindle 38 and chucks 51 will move inwardly to the position shown in Figure 3 in which the annular grooves 55 are in registry with the beading ribs 99 and the shoulders 53 are in registry with the shoulders 103 of the flanging bars. Continued rotation of the drive shaft 26 will cause the can body to traverse the inner edges of the beading bars 96 and flanging bars 97. Meanwhile, because of frictional engagement of the can bodies with the beading bars and flanging bars the can bodies will roll along the bars 96 and 97. It will thus be apparent that beads 101 and flanges 102 will be formed on the can bodies. When each can body, after completion of the beading and flanging operations, reaches the station B, a deflector bar 103 will deflect it to the exit chute 18.

As illustrated in the drawings, positive means such as the sprockets 49 and a chain 42 are provided for positively rotating the spindles 38 and chucks 51 about their own axes. However, it is not necessary to provide any such means. In most cases, if not all cases, frictional engagement of the chucks 51 with the can bodies will cause rolling of the can bodies.

During the beading and flanging operations, the chucks 51 and the seaming and flanging bars 96 and 97 are, of course, held in operative relation to each other. In prior beaders this is accomplished by moving the beading rollers radially inwardly toward the can bodies and holding them in engagement with the can bodies during the beading operation. The chucks or beading spindles are not moved radially.

By way of contrast in the beading machine of my invention the chucks 51 are mounted for radial movement as well as for rotative movement about the central axis of the machine and reciprocating movement transversely of the beading and flanging bars. Also, the chucks 51 are pivotally mounted and are subjected to a constant yielding force which is exerted in an outward, radial direction. This type of mounting and its mode of operation and significance will now be described.

Referring to Figures 4 and 5, each sleeve 37 is formed at each end with an arm 110 which is pivotally mounted on pivot pin 111. The pivot pins 50 are clamped to bosses 112 formed on the slide 34. The slide 34 is formed with two projecting lugs 113 and the sleeve 37 is formed with a projecting lug 114 having a slot 115 to receive a screw 116. A gib 117 bridges the gap between the lugs 113 and is bolted thereto by means of screws 118, and it is formed with a slot 119 to receive the screw 116. A coil spring 125 is mounted on the screw 116 and is compressed between the lug 114 and a square nut 126 which is prevented from turning by an angle bracket 127.

It will be apparent that each spring 125 will constantly urge its spindle 38 and chuck 51 outwardly and will urge the lugs 113 against the gib 117. In this position each chuck 51 will bear firmly against a can body and will hold the can body firmly against the bars 96 and 97. However, each chuck will yield inwardly whenever an extra thickness of metals is encountered, as at a side seam.

Means are also provided for adjusting the machine for can bodies of different diameters and different heights. Adjustment for can bodies of a different diameter can be made by removing the turret plates 67 and replacing them with tur-

ret plates having pockets 68 of the proper radius (see Figures 1 and 2). Adjustment for can bodies of a different height is accomplished by the means shown in Figure 6.

Referring to Figure 6, one of the cams 45 is there shown and it is provided with an extension or hub 130 which is formed with a flange 131. The flange 131 is bolted to a flange 132 which has a hub 133 formed with two diametrically opposite bosses 134, only one of which is shown in Figure 6. A threaded rod 135 is provided which is fixed at one end by means of a set screw 136 to one of the bosses 134, and which extends through an end casting or leg 137 of the frame of the machine. Nuts 138 and 139 are threaded onto the rod 135 on opposite sides of the casting 137. A smooth, unthreaded guide rod (not shown) is provided on the opposite side of the drive shaft 26.

It will be apparent that, by loosening one of the nuts 138, 139 and turning the other nut clockwise, the rod 135, and with it the cam 45, will be moved one way or the other along the shaft 26, and that one set of spindles 38 and chucks 51 can be adjusted to accommodate can bodies of a given height. When adjustment has been made, the other nut is tightened to lock the cam 45 in adjusted position. Further adjustments may also be required; e. g., when the cam 45 is shifted outwardly for taller can bodies, the adjoining spider 33 must be loosened, shifted until it is again in abutting relation to the cam 45, and then clamped to the shaft 26. Also, adjustment of the right-hand chuck 51 may be necessary; e. g., it may be necessary or desirable to substitute a shorter or a longer end portion 56.

Among the advantages of the machine thus described and illustrated may be mentioned the following:

The beading and flanging operations are performed by tools (i. e. by the beading bars 96 and flanging bars 97), which are stationary. The only moving parts are the central drive shaft 26 and the parts carried thereby including the spindles 38 and the chucks 51 which also have a rotary motion about their own axes and a longitudinal, reciprocating motion. The necessity of moving a beading or flanging tool into contact with a can body, then removing it, all in timed relation to a very rapidly operating machine, is completely obviated. The reciprocating and rotary motions of the chucks and spindles are relatively simple and do not present nearly as great a timing difficulty as the beading tools of prior machines. As a consequence, the machine of my invention is simple in its construction and operation and is capable of high speed, accurate and dependable performance.

The pivotal mounting and spring bias of the beading spindles and chucks are highly advantageous. As explained hereinabove, in prior beaders, beading rollers are provided which are moved inwardly by positive mechanical means to accomplish the beading operation. The complications of a positive mechanical movement are avoided in the machine of the present invention, by mounting the beading spindles and chucks for outward radial movement, and holding them normally in operative position but allowing inward yielding in proportion to the thickness of metal encountered.

The machine of my invention can also be adjusted easily and quickly for varying conditions. Thus, the chucks 51 can be readily changed to provide a greater or lesser number of beads and to provide or omit a flanging operation, as de-

sired. The beading bars 96 and flanging bars 97 can be rapidly and accurately adjusted by the screw mountings illustrated in Figure 3. The machine is easily adjusted for can bodies of a different height by the means illustrated in Figure 6, and it is equally easily adjusted for can bodies of a different diameter by substitution of turret plates 67.

Yet another advantage resides in the particular structure of the chucks 51. Referring to Figure 3, it will be seen that the chucks comprise identical intermediate or body portions 54, each of which has two seaming grooves 55. If it is desired to form a middle bead 101 on can bodies, then an end portion such as shown at 56 is fitted on the right-hand chuck. If a middle bead is not desired, then both chucks are fitted with end portions such as shown at 56a. In either case, the stroke of the chucks remains the same. This will be made apparent by an inspection of Figure 1. Referring thereto, it will be seen that when the chucks 51 are in their advanced, operating positions as shown at the top of Figure 1 (and in Figure 3), the two chucks will touch, or nearly so, and that the center beading groove 57 and the center beading bar 91 coincide with the center of the can body. When retracted as shown at the bottom of Figure 1, the left-hand (or short) chuck 51 clears the can body by a greater margin than the right-hand chuck 51. Nevertheless, the two chucks make the same stroke, and if a small (ungrooved) end portion 56a is fitted to the right-hand chuck instead of the large (grooved) end portion 56, the stroke will remain the same. It will, therefore, be apparent that provision is made for forming or omitting a center bead, without the necessity of varying the stroke of the beading chucks and spindles.

I claim:

1. A can body beader comprising a rotary turret adapted to receive can bodies and to rotate the same in sequence about the turret axis from a receiving station to a discharge station; an arcuate beading member concentric to said turret, said beading member being adapted to bead can bodies; a plurality of cooperable dies mounted for rotation about the turret axis in juxtaposition to said beading member, said dies being also mounted for reciprocation transversely to said beading member; means yieldably urging each die toward said beading member; means for positively rotating said dies; and means for reciprocating the same in timed relation to rotation thereof to hold each can body received by the turret in operative relation to said beading member as it is carried by the turret and to release the same at the discharge station.

2. A can body beader comprising a rotary turret adapted to receive can bodies and to rotate the same in sequence about the turret axis from a receiving station to a discharge station; an arcuate beading member concentric to said turret and spaced radially therefrom, said beading member being adapted to bead can bodies; a plu-

rality of cooperable dies mounted for reciprocating motion transversely to said beading member and for rotation about the turret axis in juxtaposition to said beading member, said dies being also pivotally mounted for radial movement toward said beading member and being yieldably biased toward said beading member, each of said dies being also mounted for rotation about its own axis; means for positively rotating said dies with said turret; and means for reciprocating the same in timed relation to rotation of the turret to hold each can body received by the turret in operative relation to the beading member and to release the same at the discharge station.

3. A can body beader comprising a frame; a turret rotatable therein; dies for urging can bodies carried by the turret radially and outwardly into operative relation to an arcuate beading member; an arcuate beading member arranged concentrically to said turret and spaced radially and outwardly therefrom, said beading member comprising a mounting ring carried by the frame and an arcuate beading bar carried by said ring; and screw means for radial adjustment of said ring.

4. A can body beader and flanger comprising a frame, a turret rotatable therein for rotating can bodies from a receiving station to a discharge station; a ring carried by the frame, arranged concentrically to said turret and spaced radially and outwardly therefrom; a plurality of arcuate beading bars and a plurality of arcuate flanging bars; screw means mounting said bars on said ring for radial adjustment; a spider mounted for rotation with said turret; a plurality of pairs of die-and-chuck members carried by said spider, each said pair being arranged for reciprocating motion along and rotation about a common axis perpendicular to said beading and flanging bars, and being pivotally mounted for radial movement toward said bars; means yieldably urging each said die-and-chuck member toward said bars; means for rotating the turret and with it said spider and die-and-chuck members; cam means for reciprocating said die-and-chuck members in timed relation to rotation thereof to enter each can body received by the turret, yieldably urge it toward said beading and flanging bars, and release each can body at the discharge station; and means for rolling each can as it rotates with the turret.
